(57) CLAIM

The ornamental design for a container cap, as shown and described.

DESCRIPTION

FIG. 1 is a perspective view of a container cap according to a first embodiment of this design wherein the surface shading is intended to show that the central portion of the cap is opaque and the outer portion of the cap is opaque; FIG. 2 is an elevational side view thereof;

FIG. 3 is a top plan view thereof; and

FIG. 4 is a bottom plan view thereof.

FIG. 5 is a perspective view of a container cap according to a second embodiment of this design wherein the surface shading is intended to show that the central portion of the cap is transparent and the outer portion of the cap is opaque; FIG. 6 is an elevational side view thereof;

FIG. 7 is a top plan view thereof; and,

FIG. 8 is a bottom plan view thereof.
